UNITED STATES PATENT OFFICE.

MAINE D. KING, OF EAST ORANGE, NEW JERSEY, ASSIGNOR TO CHARMS COMPANY, OF NEWARK, NEW JERSEY, A CORPORATION OF DELAWARE.

DESIGN FOR A CANDY DOLL OR SIMILAR ARTICLE.

Application filed April 12, 1929. Serial No. 30,854. Term of patent 14 years.

To all whom it may concern:

Be it known that I, MAINE D. KING, a citizen of the United States, residing at 135 Harrison Street, East Orange, in the county of Essex and State of New Jersey, have invented a new, original, and ornamental Design for Candy Doll or Similar Article, of which the following is a specification, reference being had to the accompanying drawing, forming part thereof.

Fig. 1 is a front elevation of the doll, and
Fig. 2 is a rear elevation thereof;
The lines on the drawing show different colors or contrasting shades of the same color.

I claim:—

The ornamental design for a candy doll or similar article substantially as shown and described.

MAINE D. KING.
